P. Newell.
Loom Temple.

Patented Jan. 5, 1833.

Peter Howell of Waterford, New York,
No. 91.

Letters Patent.

April, January 5, 1833, Reissued December 2, 1836
The Schedule, annexed to these Letters Patent, and making
Part of the same.

To all to whom these presents shall come.

Be it known that J. Peter Howell, of the town of Waterford in the County of Saratoga, and State of New York have invented a new and useful improvement in the temple for wearing cloth, so that the following is a full and exact description of the construction and operation of the said machine as improved by me, before describing had to the annexed drawings of the same making part of this specification.

First. The framework of the said machine is made of iron, wood, metal or other suitable substance constructed with guides B, about four inches long and about three fourths of an inch in width having a space between them of sufficient width to receive the jaws D, of the temple, hereafter described. The guides B, are connected with each other upon a support of the same substance at right angles to the guides and usually in "epic with it" which support is fastened to the frame by a bolt or otherwise secured. The jaws D, of the temple are made of iron or any other suitable substance. The upper jaw D, is constructed about four inches in length and about two inches in width. The under jaw is about two inches and a half long and one inch wide connected with the upper jaw by means of a joint B, piping through a suitable distance from the mouth. A right angle with the lower jaw connects therewith a projection D, about two inches in length, concave in front, the joint which the bath of the wearing frame is fixed being produced and thereby open the jaws of the temple sufficiently wide to allow the cloth to pass. The jaws of the temple are constructed of a joint of piping the joint being fastened to the under jaw.

of the upper jaw - meeting against the projection β of the lower jaw, on the under side of the upper jaw and near the meeting of the upper and articulated two sides α , between which is a slide κ , about two and one half inches in length, projecting out about one eighth of an inch from the mouth of the jaws, which prevents any possible injury to the neck of the loom when the filling is spent. The shuttle σ is seen when the filling is spent striking the end of the slide κ , which is connected with a joint arm β , hereinafter described, constrained also from the shoulder and permit the jaws of the temple to move so far as to prevent the needle from striking them. The jaws are kept in their place by means of a joint arm β , the end of which is fastened to the support of the frame & the other end acting against the shoulder of the rib β is kept in its place by means of a spring α .

Having thus fully described the construction and operation of the temple for which I seek Letters Patent, I do declare that I do not claim the individual parts comprising the same generally, such for instance as the jaws of the spinal, or other springs; but I do claim the use of sliding jaws which hold the loom, when made upon the principle and operating in the manner of those marked D. & D. in the accompanying drawing. I do not claim the making of a temple having jaws, similar to those used by me, also having a yielding motion this having been previously done but by the employment of means essentially different from that herein described, for example, in the instrument well known among manufacturers under the name of Hillman's temple, but I do claim the combination of the respective parts of this instrument with each other in which the jaws and their appendages are made to slide by means of guide pieces, and are operated upon by springs, substantially as herein set forth. I also claim as another use of a slide operating in the manner of that marked κ in the accompanying drawing, effecting a receding motion of the jaws upon the principle set forth for the purpose of preventing any injury to the neck of the temple or the shuttle, in case of the stopping of the shuttle between the two

and the example. And I confess I do not intend
by the foregoing description and claims, to limit myself to any
particular measurement or precise form of the respective parts
of this instrument, but leaving these as I may think proper,
whilst the principle of action remains unchanged."
